UNITED STATES PATENT OFFICE.

SILAS C. DICKINSON, OF WILTON, IOWA.

ELECTRIC-CLOCK MOVEMENT.

SPECIFICATION forming part of Letters Patent No. 334,517, dated January 19, 1886.

Application filed September 28, 1885. Serial No. 178,398. (No model.)

To all whom it may concern:

Be it known that I, SILAS C. DICKINSON, of Wilton, county of Muscatine, State of Iowa, and a citizen of the United States, have invented 5 an Improved Automatic Electric Clock Movement, of which the following is a full, clear, and exact description, reference being had to the accompanying drawing, forming part of this specification.

10 My invention relates to an automatic electric circuit-closing device, and is particularly adapted to be used in connection with the mechanical movements of clocks and other time-pieces, and similar mechanisms; and my invention consists in the combination of devices 15 hereinafter particularly described, and as more at length recited in the claims.

In the drawing is shown the devices embodying my invention, in elevation, in connection 20 with the actuating mechanism of a clock.

A is an electro-magnet.

B is an armature pivoted at b and extended to form an armature-lever, B'.

C is a spring rigidly held at one end by a 25 suitable clamp, as shown at c, or other equivalent device, and with its free end in line, or substantially so, with the armature-lever, as shown.

At D is shown a drum mounted to revolve 30 on a shaft, d, and placed intermediate the armature-lever and the spring C, as shown. This drum has fixed to it a ratchet, D', furnished with a pawl, d'. A cord, E, is secured at one end to the armature-lever, preferably 35 by an adjusting-screw, e, as shown, and passes thence to and around the drum, making preferably several turns on same, and thence passes to and is attached to the free end of the spring C. The cord is of such length that 40 when the armature is in contact with the magnet the spring will be flexed, as shown in the drawing.

F is a bar arranged to slide in ways or guides, as shown, and placed immediately 45 above the end of the armature-lever, and is provided with the two depending studs or arms f and f', capable of engagement by the extremity of the armature-lever.

G and G' are two spring-bars or flexible 50 tongues, mounted in suitable clamps and placed in the circuit of the battery G², as shown.

These tongues are arranged parallel to each other, and so placed relatively to the bar F that an arm, f², carried by said bar, is capable of engagement with one of said tongues. The 55 said bar F is capable of sufficient movement in its ways to have the tongue engaged by its arm f² thrown or drawn into contact with the other tongue when said bar moves in one direction, and to be released from such contact 60 by the movement of the said bar in the reverse direction. The tongues have the contact-points f³, as shown.

It is evident that when the tension of the spring C has drawn the armature-lever so as 65 to swing it to and bring it in engagement with the arm f' of the bar F, the said bar will be carried in the same direction by the action of the spring until the arm f² thereof causes the tongue G to be in contact with the tongue G'. 70 When this has occurred, the circuit is thereby closed and the electro-magnet A is instantly excited and attracts the armature B. As the armature moves to the magnet, the armature-lever pulls upon the cord E, rotates the drum 75 D, and flexes the spring C. When the armature has come in contact with the magnet, the end of the armature-lever should engage the arm f of the bar F, and throw the bar reversely so that its arm f² releases the tongue G, which 80 thereupon retreats from the tongue G', whereby the circuit is broken. The spring C being thus released, operates through the drum and its ratchet and pawl to rotate the shaft d. This 85 operation, and the alternate opening and closing of the circuit, and the consequent rotation of the shaft in one direction are continuous.

The above-described devices are specially adapted to maintain a clock mechanism in constant motion. In the drawing the drum is 90 shown on the shaft carrying the operating-pinion of a clock, as at H, and the escape-wheel I and pendulum K are shown. As the circuit is closed by the tension of the spring, the clock-pinion will be revolved, and during 95 the instant when the circuit is closed the pendulum will by its momentum continue the revolution of the pinion, the drum being during this instant reversely rotated, while the spring is being again flexed by the action of 100 the magnet and armature. The circuit being then immediately broken, the spring will again

act through the cord and drum to maintain the movement of the pinion.

It will be understood that any other form of spring than that shown at C may be employed, so that a weight may be substituted therefor. It will be further understood that any known and equivalent devices may be substituted intermediate the spring C and the armature-lever to give to the shaft d the continuous motion in one direction, as set forth.

What I claim as my invention, and desire to secure by Letters Patent, is—

1. The combination, with an electro-magnet and its armature-lever, and the spring C, and shaft d, and devices, substantially as described, whereby the tension of said spring operates to rotate the shaft, of the bar F, carrying arms f, f', and f'', and movable, as described, and the tongues G and G' in the battery-circuit, constructed and arranged to operate as and for the purpose specified.

2. The combination, with an electro-mag-

net and its armature-lever acted upon by mechanism, substantially as described, to be drawn from the magnet, of the sliding bar F, carrying the arms f, f', and f'', and the parallel tongues or bars G and G', placed in the battery-circuit, and constructed and arranged to operate as and for the purpose set forth. 25

3. The combination of the magnet A, armature B, carrying armature-lever B', spring C, drum D on shaft d, with its ratchet D', and pawl d', the cord E, sliding bar F, carrying arms f, f', and f'', and the flexible tongues G and G', in the battery-circuit, together with 30 the pinion H, escape-wheel I and pendulum K, in a clock mechanism, all constructed and arranged to operate as and for the purpose specified. 35

SILAS C. DICKINSON.
